UNITED STATES PATENT OFFICE.

ALEXANDER McIVER, OF SCHENECTADY, NEW YORK, ASSIGNOR TO GENERAL ELECTRIC COMPANY, A CORPORATION OF NEW YORK.

SYSTEM OF MOTOR CONTROL.

No. 874,025.

Specification of Letters Patent.

Patented Dec. 17, 1907.

Application filed March 9, 1905. Serial No. 249,095.

To all whom it may concern:

Be it known that I, ALEXANDER McIVER, a citizen of the United States, residing at Schenectady, county of Schenectady, State of New York, have invented certain new and useful Improvements in Systems of Motor Control, of which the following is a specification.

The present invention relates to systems of control and more particularly to motor control apparatus of the separately actuated contact type, in which a plurality of individual contacts are arranged to close in automatic progression.

It is the aim of control apparatus of this character to regulate the current input to the motors in such a manner that a too rapid increase of current is impossible, and means is usually provided for stopping the progression of the contacts or switches when the motor current rises above a predetermined, safe value, together with devices controlled by dash pots or similar mechanism for causing an interval of time to elapse between the closing of successive contacts. Dash pots require considerable attention to render them efficient, and where a single dash pot governs a number of separate elements, proper adjustment is difficult.

The object of the present invention is to provide a simple motor control apparatus of the separately actuated contact type, in which the individual contacts or switches are caused to close in automatic progression and a definite interval of time is caused to elapse between the closing of successive contacts, without the use of dash pots or other mechanism requiring careful adjustment.

To the above ends I associate with each of the main switches a controlling relay which is in turn controlled by the switch itself, whereby the actuating circuits for the switches are broken by the relays and are not again closed until the corresponding switches are closed and the relays deenergized. By this means it is impossible for two successive switches to close immediately one after the other as may occur in systems in which a single so-called time interval relay is used to control the successive operation of all the switches.

The present invention will be more clearly understood and further objects thereof will

appear in connection with the following description of several modifications thereof.

In the accompanying drawing, Figure 1 illustrates diagrammatically one form of the present invention; Fig. 2 is a similar view showing another form; and Figs. 3 and 4 show the mechanical construction of a switch and its auxiliary contacts.

Reference being had to Fig. 1, M represents a motor having one terminal connected to ground and its other terminal adapted to be connected to a current collecting device T. R¹ to R⁴ are resistance sections arranged to be included in the motor circuit and to be successively cut out or shunted by means of the main switches A, B, C and D. F is a switch for completing the motor circuit. S is a master switch. Upon closing the switch S, engagement is first made between the arm s and the contact s', thereby permitting current to flow from the current collecting device T through the switch S, actuating coil f of the switch F, auxiliary contacts associated with main switches A, B, C and D, to ground. Switch F is thereupon closed, and current flows from current collector T, through switch F, resistances R¹ to R⁴, through motor M, to ground. If, now, the arm s is brought into engagement with the fixed contact s', a second control circuit is established for causing the main switches A, B, C and D to close progressively and cut out the resistance section by section, until the motor is connected across the line with no resistance in circuit.

The present invention relates particularly to the means for controlling the switches A to D, which is as follows:—Associated with each of the switches A, B and C is a set of auxiliary switches similar in each case. These auxiliary switches comprise fixed contacts arranged in pairs as 1 and 2, 3 and 4, 5 and 6, and 7 and 8, adapted to be bridged, respectively, by movable contact members 9, 10, 11 and 12. The movable members 9 to 12 are arranged to move in unison with the movable members of the main switches and, in order that this movement may be effected, the movable auxiliary contacts may be connected directly to the movable members of the main contacts, as by means of the stems 13. It is evident, however, that the movement of the auxiliary contacts may be controlled in various other ways. Each of the switches A, B and C has also associated

therewith a relay G, G' or G'', each of which comprises an electromagnet g , to the core of which is secured a movable contact piece g' arranged, when the electromagnet is deenergized, to bridge fixed contacts g^2 and g^3 , and, when the electromagnet is energized, to connect together contacts g^4 and g^5 . An additional relay H common to all of the switches is provided. This relay consists of an electromagnet having two coils, a coarse coil h arranged in the motor circuit, and a fine coil h' arranged in the actuating circuit of the main switches A to D. The core of the electromagnet carries a movable contact piece h^2 which bridges the fixed contacts h^3 and h^4 when the relay is deenergized. The various electrical connections between the auxiliary contacts and the relay contacts will appear upon tracing the control circuits.

20 The normal condition of the parts is that illustrated. Upon moving the switch S to its final position, the main switch F will be closed in the manner previously described, and current will flow from the current collecting device T through the switch S, coil h' , of relay H, contacts of relay H, actuating coil of relay G, auxiliary contacts 5, 11, and 6 of the auxiliary contacts associated with main switch A, actuating coil a of the main switch A, wire 14, to ground. The relay G is quick-acting so that immediately upon the completion of the circuit of the relay, the movable contact member of the relay is lifted and the actuating circuit for succeeding main switches is broken but a second actuating circuit is established for the actuating coil of the main switch A,—namely, from the switch S, through the coil h' , through wire 15, contacts g^5 , g^1 and g^4 , and actuating coil of relay G, and through the coil a as before. The main switch A and the relay H act more slowly than the relay G and are both operated subsequently to the operation of the relay G. In closing, the main switch A establishes a maintaining circuit for itself, namely, the actuating circuit of the coil f is interrupted at the contacts 1 and 2 and is again completed at contacts 3 and 4,—whereupon it passes through the actuating coil a , and then through wire 14, to ground, as before. Switch A will be held closed as long as the switch S is held in its first or its second operative positions. It is noted that relay G remains energized until the main switch A is closed, and, since the relay G controls the actuating circuit of the switch B, the actuating coil of this latter switch cannot become energized until the main switch A has closed and the core of relay G has subsequently dropped.

25 30 35 40 45 50 55 60 65

The function of the relay H is to prevent the switches B, C and D from closing whenever the motor current is above a predetermined value. This is accomplished by means of the coil h of the relay which is in

the motor circuit and which serves to maintain the core of the relay lifted whenever the motor current exceeds a predetermined value.

The actuating circuit for the main switch B passes through the contacts 7 and 8 associated with the main switch A through the contacts g^2 and g^3 to the relay G, and through the contacts of the relay H; consequently it is impossible for switch B to close except when all of these contacts are in their closed positions, namely, switch A must be closed, the relay G must be deenergized and the core of relay H must be in its lower position. It is evident, therefore, that it is impossible for switch B to close immediately after switch A closes, since a predetermined time interval must elapse after the switch A has been closed, by reason of the dropping of the core of relay G, since this relay is only deenergized upon the closing of the main switch. This interval of time is ample to permit the relay H to become fully actuated and to be held in its circuit breaking position if the motor current is being increased too rapidly. An additional time interval is provided owing to the mechanical construction of the switch units to be hereinafter described.

When the parts are in the positions shown, and the switch S and the main switch A, together with its auxiliary contacts, have been actuated, current flows from the current collecting device through the switch S, through the coil h' of relay H, through the contacts of this relay, through the lower contacts of relay G, auxiliary contacts 7 and 8 associated with the main switch A, through the coil of relay G', through contacts 5 and 6 of the auxiliary contacts associated with main switch B, through the actuating coil b , wire 14, to ground. Thereupon relay G' is quickly operated, the main switch B is closed and the contacts at relay H are opened, and, upon the closing of main switch B, the relay G' is again deenergized. All these operations take place in precisely the same way and in the same sequence as the similar operations which serve to close the main switch A, and which have just been described. Similarly, switches C and D are operated, each a predetermined interval after the preceding switch, and then only when the motor current is less than a predetermined value. Since switch D is the last of the group adapted to close in automatic succession, no auxiliary relay is necessary for this switch and the auxiliary contacts corresponding to contacts 7, 8, and 12 of the remaining switches are omitted since these auxiliary contacts operate only to complete the actuating circuit of a following switch.

In Fig. 2 I have shown a somewhat different construction, in which the main relay H is omitted and each of the auxiliary relays is provided with a throttle coil in series with

the motor, whereby the auxiliary relays do not necessarily drop when the circuits of their actuating coils are broken, but do so when the motor current is within safe limits.

5 All the switch mechanism in this figure is the same as that in Fig. 1, with the exception of the relays themselves.

The relays associated with switches A, B and C, are designated by the characters K, K', K'', respectively and are alike in every respect. Each of these relays comprises an actuating coil k , a throttle coil k' , and a core carrying a movable contact member k'' which co-operates with fixed contacts k^3 and k^4 .

10 Upon closing the switch S to its final position, switch F is first closed as before, and then current passes from the current collecting device T through contact s^2 of switch S, wire 16, coil k of relay K, auxiliary contacts 5 and 6 associated with the main switch A, actuating coil a , to wire 14, thence to ground. The actuating circuit for successive switches passes through the contacts k^3 and k^4 of the relay and also through the auxiliary contacts 25 7 and 8 associated with the main switch A. Consequently both of these sets of contacts must be concurrently bridged in order for a succeeding switch to be closed. The relay K is made quick-acting like the relays G—G² of Fig. 1, so that its contacts are broken before the main switch has time to close. When the main switch closes, its actuating circuit and that of the relay K is broken at contacts 5 and 6, but a maintaining circuit for the main switch is established at contacts 3 and 4 as before. When the main switch A closes, the auxiliary contact member 12 bridges the contacts 7 and 8 so that, as soon as the contacts of the relay K are closed, the actuating circuit for the following switch B is established. If, upon closing the switch A, the motor current is increased to too great an amount, the current passing through throttle coil k' of the relay K is sufficient to hold the core of the relay in its raised position, and therefore the actuating circuit for the next succeeding switch is not closed until the motor current again drops within safe limits and permits the core 40 of the relay to fall. In the same manner switches B, C, and D are closed, but each one only after the closing of the switch immediately preceding and when the motor current is within prescribed limits.

45 In each of the modifications illustrated, the main switches, except the first, are positively prevented from closing until a definite interval of time has elapsed after the closing of a succeeding switch. This time interval is obtained without the use of dash pots or devices for retarding the various elements after their actuating means have been energized, and has at all times a definite value and one which will allow ample time for the

throttle to act in case the closing of a switch 55 has caused too great a rise in the motor current.

In Figs. 4 and 5 I have illustrated a construction of main and auxiliary switches suitable for use in systems arranged in accordance with the present invention. The mechanical construction of this switch mechanism forms no part of the present invention, however. The main switch comprises fixed and movable contacts 17 and 18, respectively, the contact 18 being carried upon the outer end of an arm 19 which is in turn supported at the inner end upon a bow spring 20. The core 21 of the actuating electromagnet 22 is pivotally connected to a lever 23 at 24, this lever being in turn pivoted to the fixed frame, as at 25. Motion is transmitted directly to the lever 23 by the core 21 and thence to the arm 19 through a spring 26 located between the said arm and the lever 23. The spring 26 permits the core 21 and the lever 23 to move a short distance after the contacts 17 and 18 come into engagement. The movable auxiliary contact members, 9-12, are slidably mounted upon a stem 27 which is guided at one end by a bracket 28 and secured at its other end to a lever 29. The contact members 9-12 are arranged in pairs between collars 30, 31, and 32, 33, and the members of each pair are 95 spaced apart by springs 34 and 35. The lever 29 is pivoted to the frame at 36 and is loosely connected to the lever 23 at 37.

The parts are shown in the positions which they occupy when the main switch is closed, 100 the auxiliary contact members 9 and 11 being in engagement with their co-operating fixed contacts. When the main switch is opened contacts 10 and 12 engage with their co-operating contacts and the collars 30 and 32 hold the contacts 9 and 11 away from their co-operating contacts. When the electromagnet 22 is energized, the core thereof rises, the contacts 17 and 18 are brought into engagement with each other and then, as 110 the spring 26 is compressed, contacts 10 and 12 are retracted and contacts 9 and 11 placed in operative position. The main switch is therefore fully closed before the auxiliary contacts are actuated and, by properly adjusting the parts, any desired time interval 115 may be caused to elapse between the closing of the main switch and the operation of the auxiliary contacts associated therewith. This time interval is sufficient to enable the 120 motor current to reach its maximum value after the closing of a main switch and before the actuating circuit of the relays is broken.

125 Although I have shown and described the two best forms of the present invention now known to me, I do not desire to limit the present invention to the particular forms shown, or either of them, except to the ex-

tent indicated in the appended claims, since in its broader aspects the present invention may be embodied in various forms.

What I claim as new and desire to secure by Letters Patent of the United States, is,—

1. In a controller, a series of switches arranged to close in automatic progression, and relays mechanically independent of the switches for positively causing a predetermined interval of time to elapse between the closing of successive switches.

2. In combination, a series of switches arranged to close in automatic progression, and means associated with each of certain of said switches mechanically independent thereof for causing a predetermined interval of time to elapse between the closing of each of said switches and the succeeding switches.

3. In a controller, a series of switches arranged to close in automatic progression, and a separate relay associated with each switch for controlling the operation of a succeeding switch.

4. In combination, a series of switches arranged to close in automatic progression, a relay associated with each of a plurality of the switches for controlling the operation of succeeding switches, and means operatively related to each of said switches for controlling its relay.

5. In a controller, a series of switches adapted to close in automatic progression, electromagnetic actuating means for said switches, and means mechanically independent of the switches for completing the circuit of the actuating means for one switch a predetermined interval of time after the preceding switch has been closed.

6. In a controller, a series of switches arranged to close in automatic progression, a relay associated with each switch for controlling the operation of a succeeding switch, and means associated with each switch for controlling the relay and a succeeding switch.

7. In a controller, a series of switches adapted to close in automatic progression, electromagnetic controlling means for each switch, a relay associated with each switch for producing a definite time interval between the closing thereof and of the next succeeding switch, and auxiliary contacts associated with each switch for controlling the electromagnetic controlling means of a successive switch.

8. In combination, a series of switches adapted to close in automatic progression, electromagnetic actuating means for each

switch, a relay associated with each switch for controlling the actuating means of a succeeding switch, and auxiliary contacts associated with each switch for controlling its relay and the circuit of the actuating means of a succeeding switch.

9. In combination, a series of switches adapted to close in automatic progression, electromagnetic actuating means therefor, a relay associated with each switch and controlling the actuating circuit of a succeeding switch, and auxiliary contacts associated with each switch for controlling the relay.

10. In combination, a series of switches adapted to close in automatic progression, electromagnetic actuating means for said switches, electromagnetic relays associated with each of a plurality of said switches for closing the circuit of the actuating means for one switch a predetermined interval of time after the preceding switch has been closed, means for energizing the actuating means of one switch and its relay, and means associated with each switch for de-energizing its relay.

11. In a motor controller, a series of switches arranged to close in automatic progression, electromagnetic actuating means for said switches, a relay associated with each switch for controlling the actuating circuit of a succeeding switch, means associated with each switch for controlling the relay and a succeeding switch, and means controlled by motor current for preventing the automatic progression when the current exceeds a predetermined value.

12. In combination, a series of switches arranged to close in automatic progression, a relay associated with each of a plurality of the switches for controlling the operation of succeeding switches, means operatively related to each of said switches for controlling its relay, and a holding coil associated with each relay and energized by motor current.

13. In combination, a series of switches arranged to close in automatic progression, and a relay associated with each of a plurality of said switches for controlling the operation of succeeding switches, each of said relays having a coil in the control circuit and another coil in the controlled circuit.

In witness whereof, I have hereunto set my hand this 6th day of March, 1905.

ALEXANDER McIVER.
